CLAIM

The ornamental design for a truss element as shown and described.

DESCRIPTION

FIG. 1 is a top perspective view of a truss element in accordance with the present invention.

FIG. 2 is a top view thereof;

FIG. 3 is a bottom thereof;

FIG. 4 is a right end view thereof;

FIG. 5 is a left end view thereof;

FIG. 6 is a right end view thereof; and,

FIG. 7 is a left end view thereof.

The truss beam is shown with a symbolic break in its length. The appearance of any portion of the truss element between the break lines forms no part of the claimed design.
